Inventor
Julius A. Pickering

UNITED STATES PATENT OFFICE.

JULIUS A. PICKERING, OF MILFORD, MASSACHUSETTS, ASSIGNOR TO WILLIAM WALKER,
OF SAME PLACE.

MODE OF ATTACHING STRAPS TO BOOT-LEGS.

Specification of Letters Patent No. 23,532, dated April 5, 1859.

To all whom it may concern:

Be it known that I, JULIUS A. PICKERING, of Milford, in the county of Worcester, State of Massachusetts, have invented certain new and useful Improvements in the Manner of Applying Straps to Boots; and I do hereby declare the following to be a full, clear, and exact description of the same, reference being had to the accompanying drawings, in which—

Figure 1 shows a portion of the leg of a boot with my improved strap. Fig. 2 shows a section of the same through the strap and Figs. 3 and 4 show some variations in applying and securing the strap.

The same letters denote the same parts in all and the red lines show the strap in all.

In the usual way of applying the straps to boots it has been customary to leave the loop or upper part free under all the different ways of securing them whether the strap was simply sewed to one side or in fine work when the lining or the outside have been cut and the lower part or ends of the strap were secured between the parts, this leaving the loop part free to turn down be tucked in or otherwise disposed of is what my invention is designed to remedy and consists in holding that loop in a convenient neat position, and to do this make a cut through the boot leg A where it is desired to place the strap as at C D Fig. 1 cutting through both parts if there are two and passing one part of the strap on each side at

the top insert the ends between the parts at 35 the cut as shown in Fig. 2 and secure them below the cut in the usual way the place and outline of the strap being shown by the lines in red ink. The loop of the strap above the line C, D, being free the fingers can be inserted either outside or in and when left the strap is supported and held in a snug position by the leather inside the loop thus keeping the strap from interfering with any part of the dress.

It is evident that the strap may be variously arranged in different ways as Figs. 3 and 4 show two variations and various others as putting one side clear through or by stitching or fastening one side of the loop 50 to support it, all of which are mere variations of detail and not of principles of my invention.

I am aware that it is not new to cut the leather or lining of the leg to insert the 55 strap and this I do not claim; but

What I claim as new and desire to secure by Letters Patent is—

Supporting or retaining the loop or upper part of the strap in the manner and for 60 the purposes substantially as above set forth and described.

In witness whereof, I hereunto set my hand in the presence of two witnesses.

JULIUS A. PICKERING.
